US00D973047S

(12) **United States Design Patent** (10) **Patent No.:** **US D973,047 S**
(45) **Date of Patent:** **** Dec. 20, 2022**

(54) **PHONE COVER**

(71) Applicant: **Guangzhou Roiskin Technology Company**, Guangzhou (CN)

(72) Inventor: **Sam Lin**, Guangzhou (CN)

(73) Assignee: **GUANGZHOU ROISKIN TECHNOLOGY COMPANY**, Guangzhou (CN)

(**) Term: **15 Years**

(21) Appl. No.: **29/772,350**

(22) Filed: **Mar. 1, 2021**

(51) LOC (13) Cl. **14-03**

(52) U.S. Cl.

USPC **D14/250**; D14/251; D14/426

(58) **Field of Classification Search**

USPC ..... CLAIM

The ornamental design for a phone cover, as shown and described.

DESCRIPTION

FIG. 1 is a front perspective view of a phone cover of the present disclosure;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

(Continued)

The shade lines shown in the drawings indicate the character and contour of surfaces represented and should not be confused with surface ornamentation.

1 Claim, 8 Drawing Sheets
